HENRY JOSEPH ROUND, OF LONDON, ENGLAND, ASSIGNOR TO RADIO CORPORATION OF AMERICA, A CORPORATION OF DELAWARE

THERMIONIC AMPLIFIER AND OSCILLATION GENERATOR

Application filed July 19, 1926, Serial No. 123,360, and in Great Britain July 20, 1925.

This invention relates to thermionic amplifiers and the like.

The object of the present invention is to provide an amplifier in which the effect of reaction and undesired coupling, due to the inter-electrode capacity of thermionic valves, is avoided.

Several means for avoiding the reaction between the electrodes of a thermionic valve are known, such means including a balancing condenser arranged in electrostatic opposition to the self-capacity existing between the electrodes of the valve. In such arrangements it is usual to provide an inductance and capacity in parallel in the anode circuit of the valve whose grid-anode capacity it is desired to neutralize, and the neutralizing or balancing condenser is sometimes connected between the end of the inductance and capacity remote from the anode and the grid, the point of zero or earth potential being arranged to be part of the way along the inductance.

An arrangement of this kind, however, still leaves degrees of freedom for unwanted oscillations.

According to the present invention the inductances employed in the anode circuits of a plurality of valves in a multi-valve amplifier, oscillation generator or the like, of the type having anti-reaction means, are wound some of them to be astatic (i. e. so that the net magnetic fields, due to currents flowing therein, are practically zero or greatly reduced at external points) and others non-astatic, and these are arranged in a mixed way.

In one arrangement, for example, the anode inductance of the first valve is wound to be astatic and that of the second valve non-astatic, the third astatic, and so on.

The anode inductances required to be astatic may be formed each of two halves wound in opposite sense, so that the mutual inductance of each half with respect to the rest of the apparatus is in the opposite sense to that of the other half.

Unwanted oscillations in other degrees of freedom can be prevented by this arrangement, which, while maintaining the same in-

ductance for the wanted natural period in both static and astatic coils, renders the inductance for other methods of oscillation very different.

The invention is illustrated in the accompanying drawing, which shows in diagrammatic form an amplifier having three valves in cascade.

Referring to the drawing, 1 is a thermionic valve in whose anode circuit is included an anode condenser 2, and an anode inductance formed of two halves 3a and 3b. 4 is a balancing condenser connected to the grid of the thermionic valve 1 and of such value as to compensate in known manner for the self-capacity of the said valve. The anode circuit is completed through the anode battery 5 from a point between the halves 3a and 3b of the anode inductance. The circuits of the valves 6, 7 are similar, like numerals indicating like parts. The anode inductance of the valve 1 is wound to be astatic; that of the valve 6 non-astatic, and that of the valve 7 astatic.

In the figure, only such parts as are necessary to explain the invention have been shown; for example, the filament heating battery and its associated connections have been omitted.

Having described my invention, what I claim is:

1. In an impedance resistance coupled cascade relay having a vacuum tube in each stage thereof, means for coupling the vacuum tubes of the several stages including an inductance between adjacent stages composed of two portions, one of which is in the output circuit of the preceding tube, alternating ones of said inductances being astatic to prevent electromagnetic coupling between said stages and means in each stage providing a path for neutralizing the inherent feed back between the output and input circuits of each stage.

2. In a cascade amplifier having a vacuum tube in each stage thereof, means for coupling the vacuum tubes of the several stages including an inductance between adjacent stages, said inductance having two portions, one of which is connected to the output elements of

the preceding tube, alternating ones of said inductances being wound astatic to prevent electro-magnet coupling between stages, and a capacity connecting another portion of each 5 of said inductances to the grid electrode of the preceding tube to neutralize the inherent capacity between the grid and anode electrodes thereof.

3. In radio apparatus, a thermionic tube 10 having anode, cathode and grid electrodes, an input circuit including an inductance associated with the grid and cathode of said tube, an output circuit connected between said anode and said cathode, and an inductance 15 consisting of two astatic wound portions, one of which is connected in series in the output circuit of said tube, the other portion of said inductance being connected through a capacity to the grid of said tube whereby the anode 20 to grid capacity of said tube is compensated and magnetic coupling between the input and output circuits of said valve is prevented.

4. In radio apparatus, a plurality of thermionic tubes each having anode, cathode and grid electrodes, an input circuit including an inductance associated with the grid and cathode of one of said tubes, an inductance consisting of two astatic wound portions one of which is connected between the anode and 25 cathode of said tube, the other portion of said inductance being connected to the grid of said tube, means for coupling the anode electrode of said last named tube to the grid electrode of the other of said tubes including a coupling condenser, a resistance connected between the grid and cathode of said second named tube, and an output circuit associated with the anode and cathode of said last named 30 tube.

5. In radio apparatus, a thermionic tube having anode, cathode and grid electrodes, an input circuit including a capacity connected to said grid electrode and a resistance connected between said grid electrode and 45 said cathode, an output circuit including an inductance having two portions one of which is connected between the anode and cathode of said tube, capacity means for connecting the other portion of said inductance to the 50 grid electrode of said tube, a second thermionic tube having anode, cathode and grid electrodes, a capacity connecting the anode electrode of said first named tube to the grid electrode of said second named tube, a resistance connected between the grid and cathode of said last named tube, an output circuit comprising a portion of an astatic wound inductance connected between the anode and cathode of said last named tube and capacity 55 means connecting another portion of said inductance to the grid electrode of said last named tube.

6. In an impedance coupled thermionic amplifier, a plurality of thermionic tubes, 60 each having anode, cathode and grid elec-

trodes, an inductance connected to the anode electrode of each of said tubes, said inductances comprising one portion connected in the output circuit of said tube and another portion connected to the grid electrode of said tube, a condenser bridged across both portions of each of said inductances, and a condenser inserted in the connection between said inductances and the grid electrode of each tube, alternate ones of the said inductances having the two portions wound so as to be astatic to prevent electromagnetic coupling between the stages, capacitive means connecting the anode electrode of each of said tubes to the grid electrode of the following tube, and a resistance connection between the grid and cathode of each of said last named tubes.
